(No Model.)

W. M. JACKSON.

METHOD OF DISCHARGING PROJECTILES.

No. 387,517.

Patented Aug. 7, 1888.

UNITED STATES PATENT OFFICE.

WALTER MARSH JACKSON, OF NEW YORK, N. Y.

METHOD OF DISCHARGING PROJECTILES.

SPECIFICATION forming part of Letters Patent No. 387,517, dated August 7, 1888.

Application filed May 23, 1888. Serial No. 274,810. (No model.)

To all whom it may concern:

Be it known that I, WALTER MARSH JACKSON, of New York, in the county of New York and State of New York, have invented certain new and useful Improvements in the Method of Discharging Projectiles; and I do hereby declare the following to be a full, clear, and exact description of the invention, such as will enable others skilled in the art to which it appertains to make and use the same.

My invention relates to hydraulic batteries, and more particularly to a method of discharging projectiles therefrom by means of water in a dynamic state of compression.

15 The method consists in compressing water until it exerts an enormous pressure, directing this water under pressure through a choked discharge-orifice, and feeding this choked discharge-orifice with projectiles—such as cannon-balls, bullets, or other missiles.

20 To carry my method into proper effect, I employ certain novel features of construction and combinations of parts, as will be hereinafter described and pointed out in the claims.

25 In the accompanying drawings, Figure 1 is a longitudinal sectional view of the apparatus preferred in carrying out my improved method; Fig. 2 shows a section of a modified form of choked discharge-orifice, and Fig. 3 is also a 30 modification.

A represents any suitable water-forcing device—simple, compound, triple-expansion, or otherwise—and actuated by any suitable power.

35 It is desirable to employ a water-forcing device capable of forcing the water from a discharge-orifice at a very high pressure—say three thousand pounds to the square inch, more or less—the higher the pressure the better the result.

40 The outlet nozzle or nozzles B are constructed of any suitable material and preferably bored straight, or may be made of a tube or tubes of great strength. This barrel or nozzle B is provided at its junction with the hydraulic supply with a plug-cock or other suitable cut-off, C. Between this cut off C and the discharge-barrel D there is placed another cock, c, which is formed by the valve-casing being swiveled upon a recessed plug, 45 d, the recesses of this plug being all around

the latter, so that no matter which way the discharge-barrel D is turned it will always be in condition for action. In order that no propulsive energy may be lost, it is absolutely essential that the projectiles should snugly fill 55 the barrel of the battery. As these projectiles are molded they are frequently very irregular and never perfectly round or spherical. Means are provided in the present invention whereby these irregular projectiles are always 60 made to fill the barrel of the battery, so that the pressure is entirely relieved in front of the projectile while every particle of energy is brought to bear upon the back of the projectile. This is effected in several ways, as illustrated in the modifications.

In Fig. 1 it is done by providing a series of ring-packings, l, about the interior circumferential area of the barrel, these rings being beveled toward the moving projectile. This 70 form of barrel is designed more especially for hard projectiles made of rigid material; but for more pliable projectiles—such as lead bullets—a simple choked muzzle or discharge-orifice, as illustrated in Fig. 2, would answer. 75

In Fig. 3 still another form of muzzle is shown. This is funnel-shaped and so located that the projectiles would roll along its lower side actuated simply by the current of the water or law of gravitation until one reached 80 the choked muzzle, when it would be instantly ejected with enormous force, the entire pressure having been applied behind the projectile, no space between the projectile and barrel being left for the exit of water. The projectiles in this case take care of themselves, 85 one following another in rapid succession, but yet never more than one at once, since only one could choke at a time.

Extending upwardly from the discharge-barrel another tube or conduit, E, the same size as the former, designated the "ammunition-conduit," is located. Close to the junction of this conduit with the discharge-barrel is located a stop-cock, e, and again, about half-way up the conduit, another cock, f, is located. Yet another cock or rather an ammunition-controller, g, is situated near the apex of the conduit. A by-pass, F, supplied with a suitable valve, h, enters the conduit just below the 90

cock *f*, and at its other end this by-pass communicates with the hydraulic supply. In Fig. 3 this ammunition-conduit is located in close proximity to the discharge - orifice, or just 5 within the choke or packing.

Above the vertical conduit a trough or chute, *G*, is stationed, the same being connected with a reservoir containing bullets, cannon-balls, or other missiles employed.

Having described the hydrodynamic gun, I will endeavor to make clear the operation. Starting the pumping-engine, I place the water in a dynamic state of compression by forcing it against a column of imprisoned air, said 15 column being contained in a receiver, *H*, located at a convenient point in the hydraulic supply and between the gun organs and the water-forcing engine *A*. As soon as the hydraulic pressure indicator reaches the desired figure— 20 three thousand pounds, more or less, to the square inch—one or more of the stop-cocks which control the feed-water to the discharge-barrel are opened, and thereupon the water immediately rushes through the discharge-barrel with tremendous velocity, discharging at 25 the muzzle. In order to make the battery effective as a weapon, it is absolutely necessary that very high pressure be employed. Nothing less than a hundred pounds to the square inch 30 would amount to anything, and five thousand pounds would be none too great. A boiler cannot be operated beyond two hundred and fifty pounds to the square inch without burning out the engine-packings, injuring all the 35 valves, and rapidly oxidizing iron and steel surfaces in the boiler, feed-pump, and engine. Hence to attain these enormous pressures some system of leverage must be introduced between the pistons operated by the 40 prime energy—such as steam and those acted upon reciprocally which force the water. There are but three ways of doing this, all resulting in securing a greater pressure to the square inch at the muzzle of the gun upon the 45 discharged water than that exerted to the square inch upon the steam-boiler—to wit, the first by having the steam-pistons larger than the water-forcing department of the engine, this being an instance of greater and less area 50 and the same time; the second, by having the steam-piston make a longer stroke than the pump-piston, both being the same size, this being an instance of leverage, the steam end being at the long and the water end at the 55 short arm of the lever; the third, by having the steam-piston make more strokes a minute than the pump-piston, both being the same size. This third method is a difference in time and consequently another phase of the lever. 60 The results of these three ways of securing the desired pressure are the same. To feed the discharge - barrel, the upper stop - cock, *g*, in the ammunition-conduit is now opened to allow bullets to drop from the chute *G* into the 65 conduit. As soon as filled, the middle cock,

f, is opened in order to let the bullets pass into the lower chamber, *i*, of the conduit. The middle cock, *f*, is now closed again and the upper chamber is refilled from the chute. It is evident that the ammunition-controller *g* 70 may be entirely dispensed with, as the object of the two chambers *i* *i'* in the ammunition-conduit is simply to measure a fixed quantity of bullets, and so prevent crowding and wedging against the stop-cocks.

Having charged the lower chamber, *i*, of the conduit or magazine with bullets, closed the middle cock, and refilled the upper chamber, *i'*, the gun is in readiness to be fired. The lower stop-cock, *e*, is now opened, as well 80 as the valve *b* in the by-pass *F*, which leads from the hydraulic supply into the lower chamber of the conduit, supplying a column of water under pressure through cock *c*. The two currents thus being equalized, the bullets 85 will fall into the barrel *D* and be hurled out with tremendous velocity. As the speed of the discharged water is much greater than that of the falling bullets, and as only one bullet at a time can be exposed to the discharged current, the bullets will follow each 90 other in very rapid succession into the barrel of the gun and be expelled much more rapidly from it; so, if the barrel of the gun be of the right length, each bullet will leave 95 the gun before the next enters the barrel. As soon as all of the bullets in the lower chamber of the conduit are discharged, the lower stop-cock, *e*, is closed, also the valve *h* in the by-pass *F*, and the upper cocks are opened, 100 so that the lower chamber will be again filled preparatory to repeating the firing.

As the bullets follow each other in such rapid succession, if the gun-barrel be swung through a part or the whole of a circle the 105 bullets may be discharged in all directions or in any one direction at will, or be made to cover a line an inch, more or less, apart, according to the speed of the whole or partial revolution of the barrel on the swivel. Thus 110 it may be seen that thousands of bullets may be discharged in a few minutes without heating the gun in the least and without smoke.

It is evident that changes in the apparatus might be made, and I do not wish to limit myself to the means shown; but,

Having fully described my invention, what I claim as new, and desire to secure by Letters Patent, is—

1. The method of discharging projectiles 120 from a hydraulic battery, consisting in dropping the projectiles into a jet of discharge-water under enormous pressure and forcing these projectiles through a choked orifice, substantially as set forth.

2. The method of discharging projectiles by forcing water against a column of air, permitting this water to pass out through a choked discharge - barrel, and dropping projectiles into said barrel, substantially as set forth.

3. The method of discharging projectiles by
forcing water against a column of air, pass-
ing the water out through a choked discharge-
barrel, and forcing projectiles from an ammu-
nition-conduit into this discharge-barrel by
means of water under equal pressure back of
said projectiles, substantially as set forth.

In testimony whereof I have signed this
specification in the presence of two subscribing
witnesses.

WALTER MARSH JACKSON.
